(57) **CLAIM**

The ornamental design for a watch, as shown and described.

DESCRIPTION

FIG. 1 is front view of my new, original and ornamental design for a watch;

FIG. 2 is a rear view thereof;

FIG. 3 is a left side view thereof;

FIG. 4 is a right side view thereof;

FIG. 5 is a bottom view thereof;

FIG. 6 is a top view thereof; and,

FIG. 7 is a bottom, front and right side perspective view of a watch shown with the moon display in a different position.

The broken lines shown in FIG. 2 are for illustrative purposes only and form no part of the claimed design.
